TRAFFIC SIGNAL

Mather Garland, Mound, Minn.

Application September 4, 1941, Serial No. 409,500

9 Claims. (Cl. 177—337)

This invention relates to visible traffic signals and traffic systems, and particularly to such a signalling system which will very effectively attract attention through animation and indicate traffic changes through distinctive, successive illumination of two or more series of lights.

Traffic signals employing signal lenses, colored lights and timed circuit controlling means have been widely used at street intersections, grade crossings and the like to indicate "go" and "stop," and oftentimes to also give a warning of traffic change. While reasonably satisfactory when disposed on street corners, central towers, or overhanging supports, they are confusing to color-blind people and oftentimes are not noticed by drivers since no particular means have been employed for attracting and obtaining the driver's attention, or causing the driver to locate the position of the signal device.

It is an object of my invention to provide a comparatively simple light-operated traffic signalling system which employs two or more series of lights mounted behind a signalling lens and each series arranged in a predetermined directional path together with time-controlled means for successively illuminating and extinguishing lights of a series through a predetermined cycle to produce a striking optical animation riveting the attention of the driver upon the signal, and to further indicate through the directional cycle of successive illumination a desired signal, even though the observer is color-blind to the extent of being unable to distinguish red from green light.

It is a further object to provide a traffic signalling system of the class described wherein traffic change signals will continue to be given even though one of the signalling lights becomes burned out or ineffective and wherein the burning out of any one of the lights will be readily indicated to an operator or traffic policeman.

More specifically, it is an object to provide a visible traffic signalling system wherein two or more lights indicating "go" are arranged in a predetermined path, and two or more lights indicating "stop" are arranged in a different and distinctive predetermined path, and wherein time-controlled circuit making and breaking means are employed to successively illuminate or flash the lights of each series in a distinctive, predetermined manner producing a distinctive, directional, optical effect upon the eyes of the observer for each of the signals given.

These and other objects and advantages of my invention will be more apparent from the fol-

lowing description made in connection with the accompanying drawings, wherein like reference characters refer to the same parts throughout the several views, and in which:

5 Figure 1 is a perspective view of one form of a signalling device embodied in my traffic signalling system, a portion of one of the signalling members being broken away to show some of the reflection compartments and lights within;

Figure 2 is a cross section taken on the line 2—2 of Figure 1;

Figure 3 is a plan view of the back of a suitable form of signalling lens detached;

15 Figure 4 is a schematic electrical diagram of the circuits and circuit-operating mechanism of the form of invention embodied in the signal devices shown in Figures 1 to 3, inclusive;

Figure 5 is a front elevation with a part of the signal lens broken away with another part of the signal device embodied in my invention;

Figure 6 is a cross section taken on the line 6—6 of Figure 5, and

Figure 7 is a plan view of the back of one of the signal lenses illustrated in Figures 5 and 6.

25 In the form of my invention illustrated in Figures 1 to 4, inclusive, one or more signal devices are employed for location either centrally of an intersection or on street corners, in which latter case two or four are utilized. As shown, each of the signalling devices comprises a box-like casing 11 having at least two rectangularly disposed, substantially vertical signalling faces provided with translucent signalling lenses 12. In the drawings the rectangular casing 11 has four of

30 such signalling faces for signalling traffic in two directions; that is, on two intersecting streets. Each of said signalling faces is provided behind the lens with a main light reflector 13 having mounted therein, as shown, three series of signalling lights, each series being arranged in a distinctive, predetermined directional path. The structure of the signal light apparatus for the several units or faces is similar, and therefore only one will be described in detail, similar reference numerals being applied to each apparatus.

35 Dish-shaped reflector 13 of each electrical signalling apparatus is divided by circularly arranged partition elements 14 into two essential concentric signalling chambers for indicating "stop" and "go." A series of circumferentially spaced "go" lights G1, G2, G3 and G4 are arranged in the "go" signalling chamber defined between the peripheral edge of reflector 13 and the partition elements 14.

40 A series of circumferentially spaced "stop"

45

lights S1, S2, S3 and S4 are mounted in the "stop" signalling chamber of reflector 13 disposed in concentric arrangement with the "go" signal lights, and, as shown, mounted inwardly of partition elements 14 and between said partition elements and a second series of partition elements 15 concentrically disposed of reflector 12.

Warning signal or "traffic change" signal lights A1 and A2, as shown four in number, are mounted in reflector 12 intermediate of the two series of lights first described, and, as shown, arranged on the four corners of a square, the two lights A1 being in vertical arrangement and the two lights A2 being in horizontal arrangement. Sector-shaped chambers are formed for these warning lights, as shown defined by radially extending partitions 16 although such partitions and chambers are not necessary for the successful operation of the signalling device.

From the foregoing it will be seen that the "go" signalling lights are arranged in a circular, predetermined directional path; that the "stop" signalling lights are arranged in a concentric and different predetermined circular directional path, and that the warning signal lights are arranged in a distinctive pattern or directional path at four corners of a square or cross.

Means are provided for transmitting distinctively colored light rays when the lights of each of said series are illuminated. While distinctively colored electric lamps may be utilized, I prefer, as shown, to provide colored, transparent or translucent panels covering the respective chambers or compartments for the several lights disposed respectively therebehind.

As shown in the drawings, the said colored panels are secured to the inner face of each of the signalling lenses 12 used, being bonded thereto by transparent adhesive or, if desired, secured thereto by any suitable means. As shown in Figure 3, sector-shaped green panels 17 constructed of colored cellulose material or, if desired, a coating of translucent paint, are applied (as shown four in number) contingent to the peripheral edge of lens 12 spaced apart by segmental amber colored panels 18 of similar material overlying the chambers for the warning signal lights A1 and A2. A second series of red colored panels 19 are disposed between the spaced segmental panels 18 and are disposed concentrically of the green panels 17 in position to overlie the chambers or the "stop" lights S1 to S4, inclusive. When the lenses 12 are properly positioned over the reflectors 13 and secured thereto by suitable means such as the rims 12a, the chambers defined by partitions 14, 15 and 16 will be properly covered with the appropriately colored panel or coating.

The several signal lights mounted in their reflector casings are supported in conventional electrical sockets and the sockets are properly wired, as shown in Figure 2, for electrical connection with circuit-controlling means and a source of electrical energy.

Electrical circuit-controlling means is provided for successively operating the several lights of each signalling series through predetermined cycles and during predetermined time periods. In the operation of each signal face the green lights G1, G2, G3 and G4 are successively flashed or operated in a counter-clockwise, circular directional path, such circulatory flashing being continued for the desired time period for traffic to move in, let us say, north and south directions. Thereafter the warning lights A1 and A2 (two in each series) are successively operated or flashed

in the predetermined vertical and horizontal paths for a relatively short interval of time. Immediately thereafter the "stop" lights S1, S2, S3 and S4 are successively illuminated in clockwise rotation and such clockwise cycle through a circular path is continued for a predetermined period of time during which traffic is stopped. The operation of the "go" and "stop" series of signal lights on the adjacent face or faces of the signal for controlling east and west traffic is similar to that described, successive illumination of the lamps of each series being in similar counter-clockwise and clockwise directions, but, of course, the "go" series of signal lights on the east and west faces of the device are operated simultaneously with the flashing of the "stop" series of signals on the north and south faces of the device.

Various mechanism may, of course, be utilized for controlling the animated illumination of the signal, and I have illustrated schematically in Figure 4 of the drawings only one form of circuit-operating means suitable for the purposes intended. The circuit-controlling apparatus may be housed within the center of the signal casing 11 or may, as will in most instances be the case, located remotely from the signal device or devices and may control the signal devices at a number of street intersections. The circuit-controlling apparatus illustrated schematically in Figure 4 includes a motor driven flasher drum 50, a distributor drum 51, and various circuits, brushes and plates related with the signalling devices. As shown, the flasher drum 50 is driven at relatively high speed direct from motor M while distributor drum 51 is driven at relatively slow speed through the large gear 52 meshed with the very small driving gear 53 mounted on the motor shaft. At the right-hand side of the sheet (Figure 4) the signal lights for one of the north and south faces of the signal and for one of the east and west faces are schematically laid out, only one of the two vertical amber warning lights being shown, and, likewise, only one of the horizontal amber lights A2 being shown since the two lamps of each set are flashed simultaneously. The development of the distributor drum is illustrated in the left-hand side of the sheet comprising an insulated drum having a metal slip ring 54 adjacent one edge thereof, said slip ring being engaged by a brush 55 which is connected by a conductor 56 with one side of the line from which the source of electricity is derived. Secured to the non-conductive drum are, as shown, four segmental contact plates arranged in staggered and successive relation, the shorter plates 57 and 58 being connectible with a brush 59 for operating the warning signal lights A1 and A2. The intermediate inner plate 60 is positioned to engage the brush 61 for operation of the green lights on one signal face and simultaneously the red lights on an adjacent signal face. The conductive plate 62 is in position to be wiped by a brush 63 for operation of the red lights on one signal face and simultaneously the green lights on the adjacent signal face.

On the flasher drum 50 two spaced slip rings 64 and 65 are provided for supplying current respectively to the red lights on one of the signal faces and simultaneously the green lights on the adjacent signalling face. Slip ring 64 is wiped by a brush 66 which is connected by wire 67 with brush 63 on the distributor drum. Slip ring 65 is wiper by brush 68 which is connected by wire 69 with the brush 61 of the distributor drum.

As shown, the flasher drum is divided by slip

ring 64 into left and right sections, each section of the non-conductive drum having mounted thereon a series of four sector contact plates corresponding to the number of lights in one of the red or green signalling series, said plates being staggered and successively disposed and electrically connected by wires with the current-feeding slip ring 64 or 65, as the case may be. Thus on the left-hand section the contact plate 70 is positioned to engage a brush 71 which is connected by wire 72 with the red light R1 of one of the signalling faces and with the green light G1 of the adjacent signal face. The next contact plate 80 on the left-hand section of flasher drum is mounted for engagement with the brush 73 which is connected by wire 74 with the red light R2 of the first signalling face and the green light G2 of the adjacent signalling face. The next contact plate 90 is positioned for engagement with a brush 75 which is electrically connected by a wire 76 with the red light R3 of the first signalling face and with the green light G3 of the second signalling face. The last contact plate 100 of the left-hand section of the flasher drum is positioned for engagement with brush 77 which is electrically connected by a wire 78 with the red light R4 of the first signalling face and the green light G4 of the second signalling face. Thus, in one rotation of the flasher drum 50 through the contacts and associated brushes at the left-hand section of that drum, the red lights on the first signalling face of the signal device will be successively illuminated in clockwise direction, while the green lights on the second signalling face will be simultaneously flashed or illuminated successively in counter-clockwise direction.

With reference to the mechanism associated with the right-hand section of the flasher drum 50 the first sector contact plate 110 is positioned to engage the brush 81 which is connected by wire 82 with the green light G1 of the first signalling face and with the red light R1 of the second signalling face. A second contact plate 120 is positioned for engagement with a brush 83 electrically connected by wire 84 with the green light G2 of the first signalling face and with the red light R2 of the second signalling face. The third contact plate 130 is positioned for engagement with a brush 85 electrically connected by wire 86 with the green light G3 of the first signalling face and with the red light R3 of the second signalling face. The last contact plate 140 of the right-hand section of the flasher drum is positioned for engagement with a brush 87 electrically connected by wire 88 with the green light G4 of the first signalling face and the red light R4 of the second signalling face.

Thus it will be seen during one revolution of the flasher drum 50, when slip ring 65 is electrically connected with a source of energy through the distributor drum during engagement of the brush 61 with contact plate 69 of the distributor drum, then green lights of the first signalling face will be flashed successively in counter-clockwise direction while the red lights of the second face of the signal will be simultaneously and successively flashed in clockwise direction.

At such times as the brush 59 on the distributor drum is in contact with one or the other of the contact plates 57 and 58, the corresponding warning signal lamps A1 and A2 (two for each signal face) are illuminated.

During the cycle of operation of the distributor

drum 51, when the sector contact plate 62 of the drum is in contact with brush 63 current is supplied to slip ring 64 of the flasher drum and the red lights of the first signal will be successively flashed in clockwise direction through the successive engagement of flasher drum plates 70, 80, 90 and 100 with brushes 71, 73, 75 and 77. Simultaneously the green lights of the second or east and west signal will be successively flashed in counter-clockwise rotation.

The flashing of the respective green and red lights and also warning signal lights, if they are flashed behind the common lens 12 of each signalling face, produces animation of light rays, giving the optical effect of circulatory light movement with considerable emanation and dispersion of light rays to attract very effectively a driver's or pedestrian's attention to the signal. The optical effect created is distinctly different because of the interposition of the common lens on each signaling face from a successive operation of independent spaced lights which are not arranged in a common reflector or behind a common lens. The successive flashing of lights through the several predetermined directional paths indicate by the directional travel of the light rays a "go" or "stop" signal and thus a color-blind person familiar with the predetermined directional path utilized may readily understand the signal, although he may not be able to distinguish green, red and amber colors.

Furthermore, since each signalling media includes a number of lights a signal will be effectively given even though one of the lights burns out or becomes disconnected. Thus the danger which is present in most traffic signalling systems is obviated, while nevertheless the burning out of one or more lights may be readily detected by an operator, traffic policeman or by the public.

In Figures 5 to 7 a somewhat different form of signalling device is illustrated, the several lights utilized for signals, however, being arranged in predetermined directional paths and being successively operated to give distinctively different animated illuminations for "go," "stop" and warning signals. In the signal device of Figures 5 to 7, four signalling faces are provided, although it will, of course, be understood that one or two may be utilized in certain installations. The apparatus for each signalling face includes a dish-shaped reflector 13 positioned vertically and divided as shown by radial partitions 150 into a series of segmental light chambers. The partitions may be eliminated, if desired, with fairly successful results. Partitions 150, as shown, extend from the periphery of reflector 13 to a cylindrical central partition 151 mounted concentric of the reflector. Within the cylindrical partition 150, as shown, reflector compartments are formed for three electric lamps G2, R2 and A2 arranged, as shown, substantially triangularly and each of said lights cooperating with two or more other lights in a predetermined directional path arrangement. As shown, the interior of the cylindrical partition 151 is divided by radial partitions 151a, although these partitions may be eliminated if desired. "Go" lights G1 and G3 are mounted in vertical arrangement aligned with the intermediate line G2 and disposed within the upper and lower segmental chambers defined by partitions 150. "Stop" lights R1 and R3 are arranged horizontally, being disposed respectively in the left-hand and right-hand segmental chambers of reflector 13 and nearly in alignment with the central "stop" light R2. Warning signal

lights A₁ and A₃ are arranged obliquely and substantially in alignment with the intermediate warning light A₂, being disposed in the appropriate segmental chambers, as shown in Figure 5.

Thus the directional flasher path of the "go" lights, which preferably give a green colored signal from the exterior of the lens 12, is up and down through a straight line vertical path. The flasher path of the "stop" lights, which preferably give an animated red signal through the lens 12, is horizontal back and forth from left to right of the signal lens, while the warning signal flasher path is oblique, giving preferably an animated amber flasher signal from the exterior of lens 12.

While any means may be used to color the rays of light emanated, I have disclosed colored translucent panels, plates or coatings applied to the inner face of the lens 12 in the same manner as in the form of the invention first described. As shown, segmental portions 152 of the inner face of the lens are covered with green material, while horizontally arranged segmental portions 153 are covered with red material and obliquely arranged segmental portions 154 are covered with amber colored material. The central part of the back of the lens is divided segmentally into three parts and appropriately covered with green material at 155, red material at 156, and amber material at 157.

Suitable electrical circuit-controlling means are provided for operating the circuits controlling the several signalling lamps of each face of the signal and the general type of circuit-controlling means illustrated in Figure 3 may be utilized, modified if necessary to apply to the particular form of signal device illustrated in Figures 5 to 7.

In both forms of the invention illustrated it will be seen that I have provided an animated traffic signalling system employing for each signal face light-operated signalling media for producing a distinctive moving optical illumination through one predetermined directional path and for producing on said face and behind a common lens another moving optical illumination through a different predetermined directional path. It will further be seen that the animation of the signals and moving emanation of light rays will attract attention to the signal, where steady illumination of one or more signalling lamps through a predetermined period will not. My improved system enables a color-blind person to readily understand the signal after becoming familiar with the several predetermined and distinctive directional paths of successive illumination. Legislation or ordinances may be passed prohibiting advertising signs and animated displays from utilizing the distinctive animated patterns for illumination which are to be utilized in traffic signals. With conventional traffic signalling systems now utilized many colored lights and flashers used in advertising often-times confuse the driver.

It will, of course, be understood that various changes may be made in the form, details, arrangements and proportions of the parts without departing from the scope of my invention.

What is claimed is:

1. A traffic signalling system having in combination, a signal device provided with a signalling face or side, a light source mounted behind said face, means associated with said light source and face for producing an illuminated rapidly moving optical effect through a predetermined

directional path, means also associated with said light source and face for producing a second and distinctively colored illuminated, rapidly moving optical effect through a different directional path, and means for timing the operation of each of said directional path cycles and for continuing the operation of each of said means through a multiplicity of cycles in each instance for a predetermined time.

2. A "stop" and "go" traffic signalling system having in combination, a signal device provided with a signalling face or side, a light source mounted behind said face, means associated with said light source and face for producing an illuminated moving optical effect through a predetermined directional path, means also associated with said light source and face for producing a second and distinctively different illuminated moving optical effect through a different directional path, means for timing the operation of each of said directional path cycles and for continuing the operation of each of said means through a multiplicity of cycles in each instance for a pre-determined time, and means for distinctively coloring the light rays emanated in said different cycles of operation.

3. A "stop" and "go" traffic signalling system having in combination, a signal device provided with a signalling face of translucent material, a light source mounted behind said face, means associated with said light source and said face for producing a rapidly moving illumination on the external side of said face through an annular path in clockwise direction, means also associated with said light source and face for producing a second rapidly moving illumination on the exterior side of said face through an annular path in a counter-clockwise direction, and means for alternately timing the operation of each of said directional path cycles and for continuing the production of moving illumination in each instance throughout a multiplicity of such cycles.

4. A "stop" and "go" traffic signalling system having in combination, a signal device provided with a translucent signalling face, a series of lights mounted rearwardly of said face and arranged in a predetermined path, a second series of contrastingly colored lights mounted rearwardly of said signalling face and arranged in a different predetermined path positioned behind a different area of said face, and time controlled means for alternately operating each of said series of lamps throughout a plurality of cycles and in said operation of each series successively and rapidly illuminating and extinguishing lights thereof through a predetermined cycle.

5. The structure set forth in claim 4, wherein each of said series of lights are arranged in a generally annular or endless path and wherein said time controlled means successively illuminates one series of said lights in clockwise direction and the other series of said lights in counterclockwise direction.

6. The structure set forth in claim 4, wherein said two series of lights are arranged in substantially straight line paths angled with respect to each other, and wherein said time controlled means successively controls illumination of said lamps in each series from one end of said path to the other and vice versa.

7. A "stop" and "go" traffic signalling system having in combination, a signalling device having a translucent signalling plate, a series of electrical lamps mounted in a predetermined generally

annular path behind said plate, a second series of contrastingly colored electric lamps mounted in a generally annular path behind said plate, reflecting means behind said lamps, and time controlled means for rapidly and successively illuminating and extinguishing the lights of one series in a clockwise direction and throughout a predetermined period of time and for rapidly and successively illuminating and extinguishing the lights of said other series in a counter-clockwise direction throughout a predetermined period of time, said time periods being such that a multiplicity of cycles of illumination of each of said series is effected.

8. The structure set forth in claim 7, and a third series of electric lamps with means for coloring the light produced in contrast to both said first and second series of lamps designed to give a warning signal, also mounted behind said face in a still different predetermined path, said time controlled means periodically operating a circuit for illustrating said last mentioned series of lamps.

9. A visual signalling system for alternately

stopping and advancing traffic having in combination, a signalling face of translucent material, a series of closely spaced electrical signal lamps mounted behind said face and arranged in a predetermined directional path, means for coloring the light produced from said series of lamps a distinctive color, a second series of closely spaced electrical signalling lamps also mounted behind said face and arranged in a different predetermined directional path, means associated with said second series and said path for coloring the light produced thereby a contrasting color to the color produced by said first mentioned members, and circuit-controlling means including a rotary driven member having a multiplicity of contacts adapted to successively and very rapidly close the electrical circuits through one series of said lamps throughout a plurality of complete cycles to indicate "go" and adapted to thereafter similarly and successively close the circuits through said second series of lamps throughout a plurality of cycles to indicate "stop."

MATHER GARLAND.
